UNITED STATES PATENT OFFICE.

AUGUST J. MOTTLAU, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTRIC HEATING UNIT.

Application filed July 19, 1924. Serial No. 726,905.

My invention relates to electrical heating units and particularly to resistor supporting means therefor.

The object of my invention is to provide 5 a relatively simple, light-weight, and easily installed heating unit for an electrically heated device.

In practicing my invention, I provide a 10 plate of metal that has a plurality of laterally extending lugs having bent-over outer ends. Refractory resistor-supporting members of electric-insulating material are interlocked with the laterally extending lugs and with the plate, and are each provided 15 with a laterally extending groove in an angular face thereof through which a resistor member extends.

In the single sheet of drawings,

Figure 1 is a top plan view of a portion 20 of a heating unit embodying my invention.

Fig. 2 is a view, partially in side elevation and partially in section, of a device embodying my invention,

Fig. 3 is a bottom plan view of a refractory resistor supporting member, and

Fig. 4 is a fragmentary view, in lateral section, of a modified form of device embodying my invention.

A heating unit 11 comprises a plate 12 that 30 is preferably made of relatively thin sheet metal of any suitable or desired contour and dimensions. A plurality of lugs 13, integral with the plate 12, are punched therefrom and are bent to extend laterally from 35 the surface of the plate and are each provided with a small bent-over end portion 14, as is more particularly illustrated in Fig. 2 of the drawings. Openings 15 are of course, provided where the lugs 13 have been 40 punched out from the bottom of the plate. The lugs 13 may be located in any suitable or desired spacing or alinement relatively to each other, and the top plan view of Fig. 1 of the drawings is more of a schematic 45 than an actual representation, of a heating unit, as the lugs 13 may be located in a spiral path on a substantially circular plate, or in any other desired arrangement, relatively to each other.

50 A refractory member 16, of a suitable electric-insulating material, operatively engages the lug 13, it being provided with a central groove 17 in one of its faces within which the laterally-extending straight portion of the lug 13 may be located, and pro-

jecting side portions 18 for preventing movement of the member 16, relatively to the co-operating lug 13. The bottom surface of the member 16 is provided with a central projecting integral portion 19 that interfits with 60 the opening 15. The projecting portion 19 prevents lateral motion of the member 16 and its action is to assist the interfitting portions of the lug 13 and the side surface of 65 the member 16. The portion 14 of the lug 13 fits over the outer surface of the member 16 and tends to prevent movement of the member 16 laterally away from the surface of the plate 12.

The members 16 are severally provided 70 with an angularly disposed surface opposite to the face having the groove 17 and a laterally extending groove 21 is provided therein to receive a resistor member 22 that is preferably of a helically wound resistor wire of 75 suitable dimensions. The resistor member 22 extends through the grooves or slots 21 and between the respective members 16.

It may be noted that the lugs 13 are so arranged and provided with the bent-over portions 14 that the open grooves 21 receive the resistor member 22 in such manner that the substantially resilient resistor member 22 tends to hold the members 16 in their proper operative engagement with the lugs 13 80 and the openings 15. In other words, the turns or winding of the resistor member 22 are such that any pull or tension of the helically wound resistor member tends to hold the refractory resistor member in its proper 85 operative engagement, substantially as illustrated in the drawings. Hence, it is only necessary to initially lay out the desired configuration of the resistor member and then to provide the bent-over portions 14 90 of the lugs 13 to co-operate therewith in view of the above-mentioned requirement.

In Fig. 4 of the drawings, I have illustrated a slightly modified design of integral lug, in which lugs 23 do not extend at substantially right angles to the face or surface of the plate 12 but extend at an acute angle thereto. The refractory resistor-supporting members 24 co-operating with the bent-over lugs 23 may be of substantially 100 the same construction as hereinbefore described for the members 16, or their form may be slightly changed, as is more particularly illustrated in Fig. 4 so that the grooves 25 are located in a substantially laterally-ex- 110

tending face of the members 24 within which a resistor member 22 may be located, as was hereinbefore described for the construction illustrated in Figs. 1 and 2 of the drawings.

The members 24 are provided with a slot or groove within which the main portion of the lug 23 may be located, as was hereinbefore described for the members 16, and 10 they may also be provided with extensions 26 that fit into the openings left by the punched-out lugs 23.

I preferably locate the heating element 11 in such position that the plate 12 does not 15 carry any cooking utensils placed thereon, but so that a cooking utensil (not shown) is supported by the bent-over portions 14 and substantially all of the heat generated by the resistor member 22 is transmitted by 20 direct radiation to the bottom surface of the cooking utensil.

Any suitable or desired means for strengthening the plate 12 to permit of its supporting a relatively heavy cooking utensil 25 may be provided, as is usual in the art.

While I have illustrated a sheet metal plate comprising integral and punched out lugs, I do not desire to be limited thereto, as the plate may be cast and the lugs will then be 30 cast integral therewith and the openings 15 will be provided by suitable core means in a manner well known in the art.

The device embodying my invention thus provides a relatively simple and light weight 35 heating unit for an electric heating device that is easily and quickly manufactured, in which the heat storage capacity has a relatively low value, and in which the heating element assists in maintaining the refractory 40 resistor supporting members in their proper positions interlocked with the supporting plate.

While I have shown and described a particular form of my invention, changes may 45 be made therein without departing from the spirit and scope thereof, and I desire, therefore, that only such limitations shall be placed thereon as are imposed by the prior art.

50 I claim as my invention:

1. In an electric heating unit, the combi-

nation with a metal plate having a plurality of spaced, integral laterally extending lugs, and a plurality of openings adjacent to said lugs, of a plurality of refractory resistor-supporting members interfitting with said lugs and said openings, each refractory member having an open groove therein, and a resistor member extending through said open groove and between said refractory members. 55 60

2. In an electric heating unit, the combination with a metal plate having a plurality of openings therethrough and a plurality of bent-over lugs extending therefrom, of a 65 plurality of laterally-grooved refractory members interfitting with said plate and said lugs, and a resistor member extending through said grooved refractory members and therebetween and effective to maintain said refractory members in their proper operative positions. 70

3. In an electric heating unit, the combination with a metal plate having a plurality of openings therethrough and comprising a 75 plurality of bent-over lugs extending therefrom to constitute a utensil-supporting means, of a plurality of refractory members interfitting with said plate and said lugs, and a resistor member extending 80 through said refractory members and therebetween and maintained thereby between said plate and the outer ends of said bent-over lugs.

4. In an electric heating unit, the combination with a metal plate having a plurality of punched-out bent-over lugs, of a plurality of refractory members, of electric-insulating material, each having a groove in one face thereof to interfit with one of said lugs and a projection on another face to interfit with the opening adjacent said lug and having also a laterally-extending groove in another face, and a resistor member extending through said groove and between said refractory members and effective to maintain said refractory members in their proper operative positions. 90 95

In testimony whereof, I have hereunto subscribed my name this 10th day of July 100 1924.

AUGUST J. MOTTLAU.
